UNITED STATES PATENT OFFICE

1,940,608

FIGURE TOY

Frederick H. Schavoir, Stamford, Conn.

Application June 13, 1933. Serial No. 675,609

10 Claims. (Cl. 46—49)

The present invention relates to figured toys such as dolls and the like, wherein the use of metallic and other members for attaching the various parts making up the toy is avoided, which metallic members are usually subject to corrosion and breakage, thereby constituting a source of danger and hazard to babies and young children.

In the usual doll construction, the arms and/or legs are secured to the body portion by providing metal hooks or projections embedded in the arms and legs to which may be secured elastic bands, cords, or metallic springs or similar devices interconnecting the arms and legs interiorly of the body portion of the doll whereby the limbs are maintained in their proper positions on the body portion. After a comparatively short period of time, it frequently occurs that the hooks will break off from the limbs so that the limbs become detached and the toy is then rendered unfit for further use. In such breakage, the sharp points of the hooks or the springs become a serious menace to a child in that serious injury might be inflicted before the damage to the doll or breakage has been noticed or observed by the parent or custodian of the child.

It is the primary object of the invention to provide a doll which may be thoroughly washed or sterilized without the likelihood of corrosion of any of the parts as would increase the likelihood of breakage or disassembly of the parts, the sterilization thereby affording a maximum sanitation.

A further object of the invention is to provide a toy of this type formed entirely of rubber so as to reduce to a very minimum the likelihood of injury to a child of very tender age.

A still further object of the invention resides in providing a novel limb construction for dolls and the like wherein the limbs such as the arms and/or legs are secured to the body portion without the use of any metallic parts such as hooks or the like. The invention contemplates an integral limb construction wherein the limbs on the opposite sides of the body portion are connected by molding an integral elastic member to the opposed joint ends of the limbs. The limbs are preferably made of molded material such as rubber with which may be formed as an integral part of the limbs the elastic connection.

A further object of the invention resides in a novel method of assembly of the doll wherein interconnected limbs are secured to the body portion of the doll by passing one of the limbs through the body portion to dispose a limb in

its proper position at each side of the body portion.

Other and further objects and advantages of the invention will be hereinafter set forth and the novel features thereof defined by the appended claims.

In the drawings, Fig. 1 is a front elevation of a doll embodying the improved features of the invention, portions of the doll being broken away and shown in section;

Fig. 2 is a fragmentary sectional view of a modified form of limb assembly;

Fig. 3 is a detail view showing the integral construction of the limbs;

Fig. 4 is a fragmentary detail sectional view illustrating the manner of assembly of the limbs on the body portion of the doll;

Fig. 5 is a fragmentary sectional view of a further modified form of the invention wherein the doll body is provided with a movable head; and

Fig. 6 is a detail view of an arm unit which is particularly adapted for use with dolls provided with movable heads as shown in Fig. 5.

Like reference characters designate corresponding parts in the several figures of the drawings.

The numeral 1 denotes generally the body portion of a toy doll which is preferably formed of molded rubber or suitable composition to which body portion the limbs are to be connected. The body portion is preferably hollow and has secured thereto in any suitable manner the head 2, also preferably of rubber and preferably integrally molded with the body portion. Suitable sockets 3 and 4 are provided in the body portion at their proper positions for the attachment of the arms 5 and 6. Similarly, sockets are provided for the legs 7 and 8.

The limb construction and manner of attachment to the body portion will be specifically described with reference to the arms, but it is to be understood that I do not wish to be limited to the application of the principles embodied therein to the arm structure, it being equally applicable to the legs as well.

Referring now to Fig. 3, the arms 5 and 6 are formed of molded compressible material such as rubber and are integrally joined together by an elastic member 7 extending between the same, the portions of the member 7 joining each arm being enlarged as at 8 and 9 to form bearing surfaces adapted to seat in the sockets 4 and 3 respectively in the body portion of the doll. In this form of the invention shown in Figs. 1 and 3, the sockets and bearing surfaces constitute what might be

95

100

105

110

called a ball socket joint, affording movement of the arms in all directions. Lateral movement of the arms is illustrated by the dotted lines in Fig. 1.

5 To assemble the arm unit shown in Fig. 3 with the body portion of the doll one arm such as 6 is inserted into an aperture 10 formed at the base of the socket 3 through the interior of the body portion of the doll in a direction as shown by 10 the arrows in Fig. 4, and outwardly through an aperture 11 in the base of the socket 4. This operation is illustrated clearly in Fig. 4. The length of the elastic member 7 is such that when one arm has been drawn through the body portion 15 of the doll, the member 7 will be stretched and placed under tension so as to draw both arms into the socket members 3 and 4 and hold them in their proper positions. By virtue of this tension on member 7, the arms will be maintained in any 20 position to which they are moved owing to the friction set up between the bearing surfaces 8 and 9 and the sockets 3 and 4. It will be observed that the apertures 10 and 11 at the base of the sockets 3 and 4 are smaller than the arms and 25 form flexible lips 12 and 13 which may be deflected or deformed as shown in Fig. 4 in the passage of the arm through the body portion in the assembling operation. After passing the arm completely through the body portion the lips 12 and 13 will spring back into place and prevent the 30 assembly from coming apart in the normal use of the toy.

While the above assembling operation has been described with relation to the passage of arm 6 through the body portion 1 it should be apparent that the assembly might be made from the opposite side by passing arm 5 through the body portion in the opposite direction.

40 A modified form of joint at the place where the limbs engage the body portion is shown in Fig. 2. In this modified construction, the structure is generally the same except that the sockets 15 and 16 are given a stepped formation for cooperation with similarly stepped bearing surfaces 17 and 45 18 formed on the arms. In this construction the joint will not be universal as in the form hereinbefore described and movement of the arms in a forward or rearward direction only is afforded.

50 As previously mentioned, it is to be understood that the leg construction may be similar to the arm construction described above in which event the same method of assembly of the legs may be followed as in the case of the arms. The arms and legs may be hollow or solid as desired.

55 Where it is desired to provide a doll of the type above described with a movable head, the elastic member 7 joining the arms 5 and 6 may be provided with a lateral extension 20, also of elastic or resilient material and preferably molded or otherwise formed integrally with the arms and joining member 7 (see Figs. 5 and 6). The free extremity of the extension 20 is enlarged as at 21 to provide a substantially mushroom shaped button or retainer head. In assembling the 60 parts, the arm unit, with the extension 20, is applied to the doll body in the same manner as hereinbefore described with relation to the other forms of the invention shown in Figs. 1 to 4, it being understood that the doll body and the arm unit are sufficiently flexible and the parts yieldable, being preferably of rubber, to enable the extension 20 and button 21 to be drawn within the doll body along with the member 7. The 65 upper end of the extension 20 with the button 21 is then drawn through an aperture 22 provided

in the upper end of the doll body, thereby disposing the button 21 exteriorly of the body. The head 23 is provided with an aperture 24 in the base or neck thereof and by passing the button 21 through the aperture 24 to dispose the same within the head, the head will be thereby movably secured to the body. In passing the button into the head, the button will flex about the extension 20 so that it may enter the head through the aperture 24, and after it has been passed completely into the interior of the head, it will automatically expand and assume its normal substantially mushroom shape as shown in the drawings, thereby preventing the head from becoming detached from the body in the normal use of the doll, while permitting the head to be turned on the body about the extension 20 as an axis. As in the limb constructions hereinbefore referred to, the head is attached to the body without any metallic parts subject to rust and breakage, and thus eliminates another of the usual sources of potential danger to children.

80 While the shoulder joint shown in Figs. 5 and 6 is similar to that of Fig. 2, it is to be understood that the particular form of joint is immaterial 85 and may take the form as in Figs. 1, 3 and 4, or any other suitable form. As a further example, the same principle of securing the head to the body may be followed in securing the arms to the body by providing buttons similar to 21 at 90 each end of the elastic member 7. If desired, the buttons might be molded or otherwise integrally formed on the doll body at the points of attachment of the arms, head and legs, and the 95 arms and legs and head snapped over the buttons as described with relation to the attachment of the head to button 21. Also, the buttons might be formed on the arms, legs and head, in which event the buttons would be snapped into the body.

100 The construction of the doll and the method of assembly should be apparent from the foregoing, and it will be obvious that there is thus provided a simple and inexpensive construction wherein the danger of injury to children due to 105 breakage of parts is virtually eliminated. Owing to the fact that the doll may be made completely of rubber the same may be completely sterilized without subjecting any parts to corrosion or rust, thereby safeguarding the health of 110 the children playing with such toy.

115 While the specific details of construction have been herein shown and described the invention is not confined thereto as alterations may be made without departing from the spirit thereof as defined by the appended claims.

120 What I claim as new and desire to secure by Letters Patent is:-

1. A figured toy of the class described comprising a body portion, and limb members formed of 125 molded material and assembled on said body portion, said limb members being disposed at opposite sides of said body portion and being joined together by an elastic member integrally molded with said limb members.

130 2. A toy doll comprising a molded rubber body portion, limb members assembled on said body portion, said limb members being disposed at opposite sides of said body portion and formed of molded rubber, and means for securing said limb members in position on said body portion, said means comprising an elastic member connecting said limb members interiorly of said body portion and molded integrally with said limb members.

135 3. A figured toy of the class described compris- 140

- ing a hollow molded body portion having limb sockets formed therein on opposite sides thereof for the reception of said limb members, said sockets being provided with apertures in the base thereof, limb members receivable in said sockets and forming joints therewith, and an elastic member extending through said apertures and integrally connected with said limb members for maintaining said limb members in said sockets, 5 said elastic member being of such length as to be placed under tension when said limb members are positioned in their respective sockets.
4. A figured toy of the class described comprising a hollow body portion formed of resilient material, said body portion being provided at opposite sides with limb receiving sockets, and said sockets being provided with apertures at the base thereof forming deflectable lips, limb members adapted to be assembled on said body portion 10 on opposite sides thereof and receivable in said sockets, said limb members being formed of molded material and including an elastic connecting member integrally molded with said limb members to extend therebetween, said connecting member being adapted to be positioned interiorly 15 of the body portion when one of said limb members is passed through the apertures at the base of said sockets and through said body portion to dispose a limb member at each side of said body portion, said connecting member further maintaining said limb members in said sockets after the passage of said limb member as aforesaid.
5. A limb unit for toy dolls and the like comprising spaced limb members of molded material, and an elastic connecting member extending between said limb members and molded integrally with said limb members.
6. The method of constructing figured toys and the like, which comprises forming a body portion to which limb members are adapted to be applied, forming limb members connected together by an elastic member integrally formed therewith, providing said body portion with apertures therethrough of a size less than the size of said limb members, and passing one of said limb 20 members through said apertures to dispose a limb member at each side of said body portion.
7. The method of assembling integrally connected limb members with a body portion of a toy doll or the like, which comprises passing one of said limb members completely through the body portion to dispose a limb member at each side of said body portion.
8. Fastening means for securing the arms and head to the body of toy dolls and the like, comprising a resilient member adapted to be positioned within the doll body and extending intermediate the arms on opposite sides of the body, said member being integral with said arms and provided with an integral lateral extension adapted to project from the upper extremity of the doll body, said projecting portion of said extension having an enlargement adapted to be positioned within the doll head and constituting a retainer for the head when applied to the body.
9. A toy doll including a hollow body, arms applied to said body on opposite sides thereof, said arms being secured thereto by an elastic member extending intermediate the arms within the body and integral with the arms, a head for said body, and means for pivotally securing said head on said body, said means comprising a member extending from said elastic member into said head.
10. A toy doll including a hollow body, arms applied to said body on opposite sides thereof, said arms being secured thereto by an elastic member extending intermediate the arms within the body and integral with the arms, a head for said body, and means for pivotally securing said head on said body, said means comprising a member 100 extending from said elastic member and integral therewith and provided at its free extremity with a flexible button normally expanded to substantially mushroom shape, said head being provided with an aperture in the base thereof for the introduction of said button through the same into the head, the size of said aperture being less than the normal expanded dimensions of said button.
